UNITED STATES PATENT OFFICE.

WALTER BROWN, OF RACINE, WISCONSIN, ASSIGNOR TO WEBSTER ELECTRIC COMPANY,
OF RACINE, WISCONSIN, A CORPORATION OF WEST VIRGINIA.

MAGNETO-MACHINE.

1,169,612.

Specification of Letters Patent. Patented Jan. 25, 1916.

Application filed May 3, 1915. Serial No. 25,416.

To all whom it may concern:

Be it known that I, WALTER BROWN, a citizen of the United States, residing at Racine, in the county of Racine and State 5 of Wisconsin, have invented certain new and useful Improvements in Magneto-Machines, of which the following is a full, clear, concise, and exact description, reference being had to the accompanying drawings, forming 10 a part of this specification.

My invention relates to magneto machines, and particularly to that class of magneto machines employed in connection with make and break ignition devices to produce the 15 ignition sparks or arcs necessary for internal combustion engine operation. The magneto is preferably of that type comprising a solid metal rotor movable in one direction by an engine driven actuating device 20 and returned quickly to normal position by springs when released from said actuator to cause a rapid change in the magnetic flux through the energizing windings of the magneto machine to cause the flow of the 25 spark-producing current. While the details of the magneto machine *per se* are not particularly important in so far as the present invention is concerned, it is essential that the movable element thereof, whether it be a 30 rotor of the solid metal type, or otherwise, be provided with means for quickly returning it to position after it has been moved from normal position and released.

The principal object of the present invention is to provide a lever whereby the movable element of the magneto may normally be moved from normal position, released and then quickly returned to normal position by 35 its associated springs to cause the flow of current and so create a spark to ignite the initial or starting charge within the cylinder of an associated internal combustion engine in order that the engine may be started without cranking. The make and break devices 40 are, of course, operated simultaneously with the operation of the magneto machine to permit passing of the spark at the proper time. In the present application I have not illustrated the engine driven actuator for 45 the rotor of the magneto machine and neither have I illustrated the make and break ignition devices, but I will say that these devices may be substantially like the corresponding devices described and illustrated in

Reissue Patent No. 13,878, granted to Emil 55 Podlesak on February 9, 1915.

The manually operable starting lever before mentioned, is designed to form a permanent part of the magneto machine with which it is associated and is so conformed 60 and related to the magneto machine that when the lever is moved in one direction, it engages the rotor, moves it from its initial position and releases the same, but when the lever is moved in the other direction, it 65 clears the rotor and thus does not operate the same in reverse direction. It is extremely important in a magneto of this type that the rotor be not moved any appreciable amount in reverse direction, this being due 70 to the fact that if the rotor is moved in reverse direction, the make and break devices will become locked or injured.

My invention is fully set forth in the following detailed description in which reference is made to the accompanying drawings, 75 in which:

Figure 1 is a front elevational view of a magneto machine embodying my invention. Fig. 2 is an isolated perspective view of the 80 manually operable starting lever. Fig. 3 illustrates the starting lever in the position which it assumes when not in use. Fig. 4 illustrates in full and dotted lines how the manually operable starting lever clears the 85 rotor when the said lever is moved in one direction. Fig. 5 is a fragmentary view illustrating how the rotor may be cocked by the starting lever after the rotor has been 90 manually moved from normal position and just prior to its being released from the starting lever.

Similar characters of reference refer to similar parts throughout the several views.

Referring to the drawings, I have shown 95 the frame-work of the magneto machine at 10, said magneto machine being provided with field magnets 11, mounted in the frame-work 10. The said field magnets are provided with suitable pole pieces (not 100 shown), located in the frame-work 10, and movable between said pole pieces is a rotor (not shown), said rotor being rigidly attached to a shaft 12. The rotor referred to is preferably in the form of a solid metal 105 inductor adapted when operated to cause a rapid change in the magnetic flux passing through the generating windings mounted

upon the pole pieces. These last mentioned features of magneto machine construction are now well known to those skilled in the art to which my invention relates, so it will be unnecessary to go into detailed description of these parts at this time.

Keyed or otherwise rigidly secured upon the shaft 12 is a yoke 13, said yoke being bent at its ends to form the arms 13^a and 13^b disposed substantially parallel to the axis of the shaft 12. Carried by the framework 10 on each side thereof and projecting from the frame-work in lines substantially parallel to the axis of the shaft 12 are arms 14 and 15 and acting between the arms 14 and 15 and the arms 13^a and 13^b of the yoke are helical springs 16—16 which normally retain the yoke and its associated rotor in the position illustrated in Fig. 1 of the drawings. Suitable rollers 17 engaged by the ends of the springs 16—16 are preferably mounted upon the arms 14 and 15 of the frame-work and the arms 13^a and 13^b of the yoke, as is clearly illustrated in Fig. 1.

Attention is directed to the fact that the magneto briefly described above is of the type wherein the rotor is oscillated and released to produce the necessary spark-producing current. Associated with the rotor 12 in practice is an engine driven actuator and make and break ignition device not herein shown but which may be and desirably are of substantially the type illustrated in reissue patent to Emil Podlesak hereinabove referred to. The arm 15 projecting from the magneto machine frame-work is preferably slightly longer than the arm 14 and mounted upon the arm 15 is a manually operable starting lever 18 having an arcuated slot 19 fitting over the pin 15, the said lever being retained in position by a washer 20 and cotter pin 21. It will be seen, therefore, that the starting lever 18 constitutes a permanent part of the magneto.

When the starting lever 18 is not in use, that is when the magneto is idle, or when the same is being operated by the engine driven actuator, the manually operable starting lever 18 assumes the position illustrated in Fig. 3. When the lever 18 is utilized to actuate the rotor, the long arm of the lever is grasped and turned in a counter-clockwise direction. As is clearly illustrated in Fig. 4, this operation of the lever will not result in actuation of the rotor, but on the other hand the pin and arcuated slot connection between the starting lever and machine frame permits the short arm of the starting lever to clear the arm 13^b of the yoke 13 associated with the roller.

After the starting lever has assumed a position illustrated in Fig. 1, the long arm thereof is operated in a clockwise direction and in this case the short arm of the lever

engages the arm 13^b and moves the rotor from its normal position. If the short arm of the starting lever is notched, as illustrated at 20, the rotor may be cocked out of its initial position just prior to being released from the starting lever, the cocked position of the rotor being illustrated in Fig. 5. After the rotor has been moved to cocked position, slight movement of the manual starting lever in the direction indicated by the arrow in Fig. 1 serves to release the rotor, whereupon the springs 16—16 quickly return the same to its initial position and simultaneously effect the generation of an electric current in the windings of the magneto machine.

It is not essential, so far as my present invention is concerned, whether the lever 18 be provided with a notch 20 whereby the rotor may be locked in cocked position. The essential feature of my present invention is the means whereby operation of the manual starting lever cannot possibly operate to move the rotor in reverse direction.

Having thus described my invention, what I claim as new and desire to secure by Letters Patent of the United States is:

1. In an ignition apparatus the combination of a current generator comprising a rotor, spring mechanism for quickly returning the rotor to normal position when the latter is moved from normal position and released, and a manually actuated lever having pin and slot connection with means fixed relative to the generator frame-work adapted when moved in one direction to engage the rotor, move and release the same, and when moved in the other direction to clear the rotor.

2. In an ignition apparatus the combination of a current generator comprising a frame-work and rotor, means for quickly returning the rotor to normal position when the latter is moved from normal position and released, and a manually operable device having pin and slot connection with means fixed relative to the frame-work adapted when moved in one direction to engage the rotor, move and release the latter, and when moved in the opposite direction to clear the rotor.

3. In an ignition apparatus the combination of a current generator comprising a rotor, means for quickly returning the rotor to normal position when the latter is moved from normal position and released, and a device for manually actuating the rotor adapted when moved in one direction to engage the rotor, move and release the latter, and when moved in the opposite direction to clear the rotor and leave the latter unaffected thereby.

4. In an ignition apparatus the combination of a current generator comprising a frame-work, rotor and means for quickly

- returning the rotor to normal position when the latter is moved from normal position and released, and a manually operable lever having a pivotal pin and slot connection 5 with a generator frame-work adapted when moved in one direction to engage the rotor, move and release the latter, and when moved in the opposite direction to clear the rotor, leaving the latter unaffected thereby.
- 10 5. In an ignition apparatus the combination of a current generator comprising a frame-work, rotor and means for quickly returning the rotor to normal position when the latter is moved from its normal position 15 and released, an arm carried by the generator frame-work and a manually operable lever adapted to releasably engage the rotor, said lever provided with an elongated slot fitting over said arm, said lever adapted 20 when moved in one direction to engage the rotor, move and release the latter, and when moved in the other direction to clear the rotor.
6. In an ignition apparatus the combination 25 of an ignition magneto comprising a frame-work, rotor and means for quickly returning the rotor to normal position when the latter is moved from its normal position and released, an arm carried by the frame- 30 work or something stationary relative thereto, and a manually operable lever provided with an arcuated slot fitting over said arm, said lever adapted when moved in one direction to engage the rotor, move and release the latter, and when moved in the 35 other direction to clear the rotor.
7. The combination of a current generator including a rotor and frame-work, a crank arm on the rotor and spring connecting the rotor and frame-work adapted 40 to return the rotor to initial position when the latter is moved from initial position and released, a pivot member carried by the frame-work and a lever having an arcuated slot fitting over said pivot member, said lever adapted when moved in one direction to engage, move and release said crank arm, and when moved in the opposite direction 45 to clear the crank arm.
8. In an ignition apparatus the combination of a current generator comprising a rotor, spring mechanism for quickly returning the rotor to normal position when the latter is moved from normal position and released, and a manually actuated lever 50 having pin and arcuated slot connection with means fixed relative to the generator frame-work, said lever adapted when moved in one direction to engage the rotor, move and release the same, and when moved in 55 the opposite direction to clear the rotor.
9. The combination of a current generator comprising in combination a frame-work, a rotor, a crank arm fixed relative to the rotor, an arm on the generator frame-work, 60 spring means for connecting said last mentioned arm with said crank arm whereby the rotor is quickly returned to initial position when the latter is moved from initial position and released, and a manually operable 65 starting lever having an arcuated slot fitting over said arm carried by the frame-work, said lever adapted when operated in one direction to engage the crank arm, move and release the same, and when 70 moved in the opposite direction to clear the 75 crank arm.
10. The combination of a current generator including a frame-work, a rotor, a yoke on the rotor, arms carried by the frame-work, springs connecting the last mentioned arms with said yoke adapted to quickly return the rotor to initial position when the latter is moved from initial position and released, a manually operable starting lever 80 having pin and arcuated slot connection with the frame-work adapted when operated in one direction to engage the rotor, move and release the latter, and when moved in the other direction to clear the rotor, and 85 means for securing the starting lever in position upon the generator frame-work.
- In witness whereof I hereunto subscribe my name this 26th day of April, A. D. 1915.
- WALTER BROWN.
